UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING-MACHINE.

1,356,926.

Specification of Letters Patent. Patented Oct. 26, 1920.

Application filed May 23, 1917. Serial No. 170,354.

To all whom it may concern:

Be it known that I, ALFRED G. F. KUROWSKI, a subject of the Emperor of Germany, (but having taken out his first but not his 5 final United States naturalization papers,) residing in Brooklyn borough, in the county of Kings, city and State of New York, have invented certain new and useful Improvements in Typewriting-Machines, of which 10 the following is a specification.

This invention relates to an improvement in typewriting machines, and more especially to tabulating mechanism, whereby the 15 position of the typewriter carriage can be controlled either to jump selectively to any one of a plurality of major columns or zones from the starting position of the carriage, or from any position preceding the zone selected, or to jump the carriage successively 20 to a plurality of predetermined major columns or zones, and at the same time select a particular decimal column or letter-space in each zone at which the carriage stops. This 25 application is an improvement on my co-pending application, No. 170,132, filed May 22, 1917 (now Patent No. 1,289,820, dated December 31, 1918).

In the form herein illustrated a single set 30 of tabulating keys is used to control the major or jump movements of the carriage. These keys, when depressed individually, operate either one of two plungers in two different groups, according to the position of a set of floating interponent levers. One set 35 of plungers, which may be designated as the decimal tabulating plungers, are projected into the path of the next succeeding one of a series of carriage-carried stops, one for each letter-space or decimal column of the carriage. That is to say, there is a series of 40 these settable stops, one in each letter-space, which may be individually set by a key provided for this purpose, which may be accomplished by striking the special key when the carriage is in a position to bring the initial 45 letter-space or decimal column of the zone selected to the printing point of the typewriter. This set of plungers and stops enable the carriage, under the control of the 50 tabulator key, to jump successively to each major column or zone and stop at certain particular letter spaces or decimal columns in each zone, according to the particular setting of the series of certain stops and decimal 55 tabulating keys actuated.

The other set of plungers may coöperate with a second set of carriage-carried stops, of which, however, there is but one for each major column or zone. The second set of plungers, with the exception of one, does not, 60 in the form illustrated, coöperate directly with this second set of stops to obstruct the travel of the carriage. The excepted one of the plungers is illustrated as operated directly by its key to move into the path of the 65 next succeeding carriage-stop in case its key is operated. It is operated also indirectly through the aid of the other plungers and keys, when any one of the other tabulating 70 keys is operated. To do this, the stops in the second set are shown as graded in their range or reach, so as to coöperate electively with a series of cam levers or selectors brought into play individually by associated 75 ones of the second set of plungers. That is to say, when any one of the tabulating keys, except one, is operated when column selecting, it will raise the associated cam lever above its fellows into the path of movement of the second set of carriage-carried stops, 80 but as these stops are graded in their reach, if it is an intermediate tabulating key corresponding to a later column than the first, one or more of the carriage stops will escape past it as the reach is too short. Inasmuch 85 as the reach of each stop increases in succession from first to last, the proper stop having the right reach will come into engagement with this cam lever, thrusting the cam lever before it and rocking a frame universal 90 to all of the cam levers. This frame is shown as connected to thrust up the only plunger in the second set which is capable of obstructing the path of movement of the second set of carriage-stops. This enables the 95 obstructing plunger to remain passive while the carriage travels, until the particular major column or zone determined by the carriage, corresponding to the tabulating key actuated, comes to the printing point, 100 when the corresponding carriage-stop will force this plunger up to its obstructing position in time to catch the same stop, and thus obstruct further movement of the carriage.

The position of the floating interponent 105 levers, and thus the character of tabulating, is illustrated as adapted to be determined by two keys, connected so that when one is in operation, the other is out of operation. These keys are designated as the "decimal 110

tabulating" key and the "column tabulating" key.

Other features and advantages will hereinafter appear.

5 In the accompanying drawings,

Figure 1 is a vertical section taken from front to rear, with parts omitted to simplify the showing. In this view, the decimal tabulating mechanism is shown in control of 10 the major traveling movements of the carriage.

Fig. 2 is a detail section of the pivot frame which forms floating supports for the interponent levers. This view shows the 15 dead center lock for holding the tabulating mechanism in either of its adjusted positions for controlling the selection of either decimal tabulating or column tabulating.

Fig. 3 is a horizontal section, showing the 20 rear portion of the tabulating key levers and the shifting mechanism for the pivot support of the floating levers.

Fig. 4 is a skeleton perspective view of the tabulating mechanism, showing the 25 floating interponent levers in coöperation with the selective major column or zone controlling plungers, as distinguished from Fig. 1.

Fig. 5 is a detail view in elevation, showing 30 one of the column zone controlling carriage stops in the act of projecting the interfering column plunger into the path of the carriage stop, so as to prevent further movement of the carriage.

35 Fig. 6 is a detail perspective view, showing the two plungers farthest to the left, and showing how the column or zone selecting plunger which does the obstructing is operated from the frame universal to the 40 camming levers or selectors.

Fig. 7 is a detail view in front elevation, showing the relation of the column or zone 45 selecting carriage stops, and the plunger mechanism therefor, before the plunger mechanism is operated, and also showing several of the decimal tabulating carriage stops as set.

Fig. 8 is a vertical section taken from front to rear, showing the relation of the 50 decimal tabulating key and the column tabulating key when the latter is actuated to control selectively the jumping to any desired major column or zone from the beginning of the line of writing.

55 Fig. 9 is a detail vertical section taken from front to rear, the parts being in the position shown in Fig. 8, except that in full lines one of the tabulating keys is shown as depressed in the act of making a major column or zone selection.

Character keys 1 depress key levers 3 to rock bell cranks 4, so as to swing type-bars 5 up rearwardly against the front side of a platen 6 mounted to rotate on a carriage 7.

60 65 The carriage 7 is controlled at the actua-

tion of the keys 1 to travel step by step in a letter-feeding direction by an escapement mechanism indicated in general at 8. This escapement mechanism includes a rack 9 hinged on the carriage 7 and engaging a 70 pinion 10, which, in turn, is controlled in its rotation by an escapement wheel 11. The escapement wheel 11 is permitted to have an intermittent movement by means of a pair of fast and loose dogs 12, rocked at the actuation of each key by means of a universal frame 13, in turn, rocked by engagement therewith of a heel 14 carried by each of the type-bars 5.

In addition to having step-by-step movements, the carriage 7 may be jumped a number of letter-spaces or decimal columns at a time to any desired zone or major column. This may be done in the present case in either one of two ways, viz., either by jumping the carriage to successive zones and to selected decimal columns or letter-spaces in such zones, or by jumping the carriage selectively from the start or any earlier point in its movement to any one of the succeeding major columns or zones, omitting or passing by one or more intermediate zones or major columns. In either case, the jump movements of the carriage are controlled by the same set of tabulating keys 15. The 95 keys 15, when depressed, rock key levers 16 which are pivotally mounted intermediate their ends, on a common pivot rod 17. Key levers 16 have associated therewith two groups of bars or plungers, one plunger in 100 each group for each key lever.

One set of these bars or plungers 18 are the decimal tabulating plungers or counter-stops for selecting particular decimal columns or letter-spaces in major columns or 105 zones.

The other set of bars or plungers 19 are for selecting any one of the series of columns or zones within the capacity of the carriage, so that the carriage may be jumped 110 from a starting position to any desired major column or zone, skipping, if necessary, intermediate major columns or zones.

To enable the tabulating keys 15 to operate selectively one or the other set of 115 plungers 18 or 19, there are provided a series of interponent levers 20, which have heads 21 to be interposed between the tabulating key levers and either the plungers 18 or the plungers 19. The interponents 20 are floatingly mounted by being pivoted on a rod 22, which is supported by a shift-frame 23. The shift-frame 23 can occupy one of two positions, corresponding to the interponents acting as an intermediary between the tabulating key levers 16 and either the plungers 18 or the plungers 19.

To adjust the shift-frame 23, there are provided a pair of keys, one of which 24 is the decimal tabulating key and the other of 130

which 25 is the column tabulating key. These keys are mounted respectively on thrust rods 26 and 27, which are pivotally connected at their inner ends to arms 28 and 5 29, forming a bell crank pivotally mounted by means of a rod 30. The arm 29 is connected by means of a link 31 to the rod 22 of the shift-frame 23. This link 31 has a projection 32 to engage the cross bar of the 10 shift-frame 23.

The two positions of the shift-frame 23, and thus of the interponents 20, are determined by a toggle lock, Fig. 2, which includes an arm 33 on the frame 23, and a collapsible spring link 34 pivotally connected to the arm 33. The spring link 34 includes a pair of telescoping tubes 35 and 36, Fig. 3, the former of which is pivoted at 37 to the arm 33, and the latter of which is pivoted at 20 38 to a fixed support. Within the collapsible link there is provided an extension spring 39 yieldingly locking the frame by passing to either side of a dead center between the pivots 38 and 39^a, as indicated in 25 Fig. 2, according to the position of adjustment of the interponents 20 and the shift-frame 23. The thrust-rods 26 and 27 for the selecting keys are guided at their forward ends in a comb 40, which is universal 30 to all the tabulating key-levers 16.

In order to enable the operation of whichever set of plungers the interponents 20 are in conjunction with, it is necessary that these plungers release the carriage from the 35 escapement mechanism 8, so that the carriage can travel under the impulse of its spring-barrel indicated at 41. To do this, the plungers 18 are provided with shelves 42, and the plungers 19 with shelves 43, 40 formed by notches in all of the plungers. The shelves 42 and 43 engage and operate a bar 44 universal to all of the plungers. This bar 44 forms part of a rock-frame 45 pivoted at 46, so that when the bar 44 is 45 forced upwardly it will rock down an arm 47 of the frame 45. The arm 47 draws down on a link 48 to rock a lever 49, carrying at its front end a roller 50, which underlies the rack 9, and thus raises it out of engagement 50 with the pinion 10. This happens when any one of the tabulating keys 15 is actuated, whether decimal tabulating or column tabulating. The carriage is then free to move until arrested by either decimal stops 51 or 55 column stops 52, according to the character of tabulating control in action at any particular time.

If the interponents are in the position shown in Fig. 1, the selection will be a decimal tabulating one, and the plungers 18, when operated against the tension of their springs 53, will come into the path of such of the decimal stops 51 as are set.

There is a series of these decimal stops 60 51, one for each letter-space or decimal col-

umn of the carriage 7. They are adjustably mounted in a supporting bar 54, so as to occupy either a passive raised position or an active depressed position. These decimal stops 51 are thus mounted in the bar 54 for 70 vertical adjustment, by being inserted in vertical slots therein and having projections 55, limiting their uppermost and lowermost positions. They may be locked in their different positions by spring-pressed ball detents 56 engaging in notches 57, provided on their edges.

Preferably, the decimal stops 51 are key set. They may be all in their raised position and the carriage moved to its extreme 80 right-hand or starting position. The carriage is then advanced to the initial letter-space of the first major column or zone desired, and a special or stop-setting key 58 depressed in the manner more particularly 85 described in application No. 140,818, filed January 5, 1917 (now Patent No. 1,229,559, dated June 12, 1917). The key 58 depresses a key lever 59, which thrusts downwardly a link 60 to rock a bell crank 61, which is connected to draw down on an angular link 62. The link is guided for vertical movement, and has an arm 63 projecting over the series of decimal stops 51, and at any particular instant stands over the particular one corresponding to the letter-space position of the carriage at that instant. It is thus evident that by moving the carriage to each position desired for the several successive zones, and depressing the decimal tabulating stop-setting key 58 at these points, the stops 51 will be selectively set to subsequently determine the position of the carriage for these major columns or zones. The stop determines the beginning of the zones, but when 100 it cooperates with the several tabulating keys 15 through the plungers 18, it will arrest the carriage at the decimal column or letter-space corresponding to the particular tabulating key 15 actuated.

There are ten of these tabulating keys 15, corresponding to ten decimal columns or letter-spaces of each zone or major column, at any one of which spaces it is possible to selectively position the carriage by a single 115 active stop 51. The tabulating keys 15 have indications thereon of the decimal spaces which they control (see Fig. 4).

To unset the decimal stops 51, there is provided a slide 64, which underlies the upper 120 extensions 55 on all the decimal carriage stops 51. This slide 64 is provided with cam slots 65 engaging pins 66 on the bar 54, so that when it is moved endwise of this bar against the tension of a spring 67, it will be 125 forced upwardly, carrying with it all of the stops 51 which happen to have been set, restoring them to an unset condition.

When the interponents 20 are in the Figs. 4 and 6 position, the tabulating keys 15 will 130

be connected to operate the major column or zone-selecting plungers 19. Only one of these plungers 19, especially indicated as a counter-stop at 68, is arranged to directly 5 obstruct the movement of the carriage by engagement with the carriage column stops 52. This plunger 68 corresponds to the first major column or zone, and is projected directly through the intermediary of one of 10 the interponents 20 by its key indicated at 69, Fig. 4, which has a designation "1" thereon, indicating that it controls the first major column or zone.

There is one of the stops 52 corresponding 15 to each major column or zone, and they are adjustably mounted at letter-space intervals on a double rack bar 70, so that they can be individually set at such a position as to be caught by the obstructing plunger 68. 20 The stops 52 are locked against accidental displacement on the double rack bar 70, by means of a locking rod 71 extending lengthwise of the rack bar 70, and universal to all possible positions of the stops 52. This bar 25 is semi-circular in cross section, Fig. 1, so as to be rotated by means of a hand-crank 72 from the Fig. 4 position, which is the locking position, to a position in which the hand-crank 72 will be at right angles to 30 its Fig. 4 position, which would be the unlocking position. The stops 52 are provided with semi-circular cut-out portions, Fig. 1, permitting this locking and unlocking of the stops.

35 The stops 52 are forked to embrace the bar 70. The upper leg of the fork is of the same length in each case, but the lower leg varies in its range or reach, increasing from a minimum for the first stop to a 40 maximum for the last stop in a step-like series. In the present case, there are shown ten of the column stops 52, corresponding to the ten tabulating keys 15, which, in addition to their decimal tabulating indications 45 above mentioned, are numbered from 1 to 10 to designate the particular major columns or zones which they control.

As stated above, only one of the plungers 19 acts as an obstructing member to determine the stopping point of the carriage 7. 50 This plunger is operated in the first place by its own key 69. In the second place, it is operated by any one of the other tabulating keys 15 through the intermediary of their plungers 19 and other mechanism which will now be described.

Each of the plungers 19 is provided with a horizontal offset 73, comprising a right angle, so that the offsets form a nest. The 60 ends of these offsets 73 lie in a straight line extending from the front to the rear of the machine, and they have loose shoulder and socket pivotal connections with camming levers or selectors 74. Each connection is 65 such that when any one of the plungers 19

is raised, it will rock the associated selector 74 upwardly, permitting it to have a subsequent relative sliding movement with respect to the associated offset 73. The selectors 74 are pivoted side by side on a rock 70 frame 75, and have projecting cam portions 76, adapted when raised to lie in the path of corresponding lower legs of the column stops 52, so as to be operated thereby. That is to say, the first of the column stops 52 75 will escape all of the selectors 74, and will engage directly with the plunger 68 when the latter is raised by its key 69. The second of the column stops 52 will clear all of the selectors 74, except the rearmost one, 80 which it will operate when it is raised to a projecting position by operation of its tabulating key 15 which has the designation "2." The third column stop 52 will clear all of the selectors 74 in front of the second 85 selector 74, and will operate the second selector when it is raised to its projected position by its tabulating key 15 which has the designation "3" thereon. The lower legs of the column stops 52 increase in range or 90 reach, so as to operate successively the rest of the selectors 74.

In this way, each column stop 52 will operate when its associated tabulating key 15 is operated, under column-selecting conditions, the corresponding selector 74, as stated before. When any one of these selectors is operated, it will rock the frame 75. This frame is pivoted at 78 and has an arm 79, Fig. 6, which engages in an opening in 100 the special or obstructing plunger 68, so as to raise it to obstructing position. The cams 76 are located slightly to the right of where the obstructing plunger 68 projects through its casing 80, so that the carriage 105 in striking the raised selector 74 will cause the selector to raise this plunger in time to catch the same column stop 52 which strikes the selector. The plungers 19, which include the plunger 68, are normally held in 110 a depressed position by springs 81, which are alternately arranged on the front and rear of the plungers to give room for the same, as the plungers are closely set together.

115 Inasmuch as the interponent levers 20 are either acted on by the springs 53 of the plungers 18 or by the springs 81 of the plungers 19, the tabulating key levers 16 will normally be held in a horizontal position with the tabulating keys 15 raised. Inasmuch as the plunger 68 is raised at times by others of the tabulating keys 15, a special spring 82 is provided for the lever of the tabulating key 69, which overlies the 120 rear end of it to prevent its dropping when the pressure on the rear end of the key lever is removed when the obstructing plunger 68 is raised through the intermediary of the other plungers and tabulating stops 52. 125 130

The plungers 18 and 19 are guided for vertical movement, at their upper ends by combs 83 and 84, respectively, Fig. 4, and at their lower ends by a comb 85. The extent 5 of vertical movement of the plungers is limited by means of rods 86 extending through slots provided in the plungers. The interponent levers 20 are held in register with the tabulating levers 16 and with 10 the plungers 18 and 19 by extending at their rear ends into the spaces between the teeth of the comb 85; and at their front ends by extending into spaces between the teeth of a comb 87, provided on the shift-frame 23.

15 The operation of the device will be readily understood when taken in connection with the above description. If it is desired to do decimal-tabulating and jump successively to each major column or zone, the decimal- 20 tabulating key 24 is pressed into the Fig. 1 position. Thus, the shift-frame 23 is rocked to bring the interponent heads 21 between the tabulating key-levers 16 and the plungers 18. The stops 51 carried by the carriage 25 may be set by the stop-setting key 58, according to the position of the several zones or columns desired. That is to say, the carriage is brought to bring the first digit space or decimal column to the printing 30 point of each successive zone, and the key 58 is depressed each time the carriage is so positioned, thus depressing the proper stop 51 to its active position. With the parts in this condition, the carriage, when started to 35 the right, will of necessity stop at each zone in succession when any one of the tabulating keys 15 is depressed. The stop 51 determines the zone, while the particular tabulating key 15 determines the selection of a certain 40 decimal column in the zone, as indicated in Fig. 4, by the designations on the tabulating keys which are from units to millions with an additional key for the decimal point.

If a different type of work is to be done, 45 wherein it is not desired to write in every major column or zone, then the other means of selection may be used, so that the operative can skip over such major columns or zones as it is not desired to write in, but can 50 arrive at the desired zone or major column instantly. For this type of work, the column-tabulating key 25 is pressed rearwardly, as in Fig. 8, thus rocking the shift-frame 23 rearwardly to bring the interponent 55 heads 21 between the tabulating key-levers 16 and the plungers 19. If it is desired to write in the first major column or zone, the tabulating key 69, Fig. 4, is operated, which, through one of the interponents 20, will project the only obstructing plunger 68 of this set into the path of the stops 52. The first stop 52, Fig. 4, will engage under these conditions the projected plunger 68, and bring the carriage to rest 60 for the first zone or major column. If any other major column or zone is desired, the corresponding tabulating key 15 having the number of the zone thereon is struck, so that it will raise its associated plunger 18, and thus raise the associated selector 74. If this 70 selector happens to be one corresponding to one of the later zones, the first few stops 52 will not reach it, as their lower legs are not long enough, and they will not operate their own selectors 74, which lie in a depressed or 75 ineffective position. There will thus be a cross selection, so that the proper column stop 52, corresponding to the tabulating key 15 actuated, will operate a corresponding selector 74, so as to rock the frame 75. This 80 frame is connected to raise the obstructing stop 68 just in time to catch the particular column stop 52, which brought it into play. The carriage will thus be stopped at the zone or major column selected as soon as the 85 depression of the tabulating key is relieved, the rack bar 9 will come into engagement with the pinion 10 and be once more under the control of the escapement mechanism, which is so arranged as to permit a fractional movement of the carriage to clear the 90 stop 52 from the obstructing plunger 68.

It will thus be seen that the carriage can be quickly positioned for major column or zone-writing in one of two ways, that is, successive zone-writing with incidental decimal or letter-space selection, or selected zone-writing, according to the requirement of the particular type of work being done. 95

Moreover, there need be no annoyance to the typist in properly positioning the stops 51 and 52 in corresponding positions, since if any stop 52 is positioned, the typist can set the corresponding stop 51 by first depressing the key 69 to position the carriage 100 by the already positioned stop 52, and then depressing the stop-setting key 58 to set the desired stop 51. It will be noted that in the device of the present disclosure the stop-setting key may be thus effective even if 110 the "column" key 25 remains depressed. Thus when it is desired to position a stop 51 for each column, the successive finger actions may be carried out practically automatically. If column-stops 52 are already set, it is also a very simple matter to change the adjustment of the decimal-stops 51 by operating the slide 64 to make them all ineffective, then spacing the carriage along by the stops 52 to set the stops 51, and if any 120 stops 51 are to be set at intermediate points, feeding the carriage along by the usual space-bar from the nearest stop 52.

Variations may be resorted to within the scope of the invention, and portions of the 125 improvements may be used without others.

Having thus described my invention, I claim:

1. The combination with a traveling carriage, of two sets of stops carried by said

- carriage, plungers to coöperate with said stops to determine the position of said carriage, tabulating keys for operating said plungers, and shifting means for selectively varying the operative connection between said plungers and said keys, so as to determine which of said stops shall be in play. 5
2. The combination with a carriage, of a set of uniform stops carried by said carriage, a set of graded stops carried by said carriage, plungers for coöperating with said stops, and a single set of tabulating keys for selectively operating said plungers, so as to selectively determine, by their coöperation with said stops, either the successive movement of said carriage to a plurality of major columns or zones or a selective movement of said carriage to any one of a plurality of major columns or zones, skipping, if necessary, intermediate zones. 10
3. The combination with a traveling carriage, of stops carried by said carriage, plungers for selectively coöperating with said stops to determine either one of two types of jump movements of said carriage, one successive movement to each of a series of major columns or zones, the other selectively to any of a series of major columns or zones, skipping, if necessary, intermediate zones, tabulating keys for controlling the action of said plungers, interponent mechanism for determining how said keys shall operate said plungers, shifting means for said interponent mechanism, a column-tabulating key for adjusting said shifting means and said interponent mechanism in one direction to effect column-tabulating, and a decimal-tabulating key for adjusting said shifting means and said interponent mechanism in the opposite direction to effect decimal-tabulating. 15
4. The combination with a traveling carriage, of a series of stops carried by said carriage, one stop for each letter-space of said carriage, a second set of stops carried by said carriage, adjustable to different letter-space positions along said carriage, two sets of plungers, one set coöperating with each set of stops to determine the position of said carriage, one set of plungers acting by any one of them operated engaging the next succeeding stop, the other set of plungers operating by only one of them engaging selectively any one of said stops, allowing certain of said stops to pass idly, according to the particular plunger actuated, and a plurality of tabulating keys for operating said plungers. 20
5. The combination with a traveling carriage, of stops carried by said carriage, two sets of plungers for coöperating with said stops to determine different types of jump movements of said carriage, tabulating keys for operating said plungers, escapement mechanism normally controlling step-by-step movements of said carriage, and shifting means for disconnecting said carriage from said escapement mechanism for a tabulating movement of said carriage, including a bar interposed between said two sets of plungers and universal to all plungers in each set. 25
6. The combination with a traveling carriage, of an escapement mechanism normally controlling step-by-step movements of said carriage, shifting mechanism for disconnecting said carriage from said escapement mechanism to permit major movements of said carriage, said shifting mechanism including a universal bar, and tabulating mechanism for controlling major movements of said carriage, including plungers arranged on both sides of said universal bar, and capable of individually engaging and operating said universal bar to disconnect, through said shifting mechanism, the carriage from said escapement mechanism. 30
7. The combination with a traveling carriage, of a set of master stops settable at any one of a plurality of letter-spaces along the travel of the carriage, devices for arresting the carriage by said stops, a separate set of stops, one for each letter-space in the travel of the carriage, and normally in unset position, separate devices coöperating with said separate set, and a stop-setting key mechanism to selectively set such stops in said separate set as are determined by the previously set master stops. 35
8. The combination with a traveling carriage and tabulating stops thereon, of a set of tabulating keys, a plurality of counter-stops for each key, a pivoted lever for each key, an interponent for each lever to enable the lever to selectively operate its plungers, and means for simultaneously shifting and guiding the interponents to selectively connect the levers to the counter-stops. 40
9. The combination with a traveling carriage, of a tabulating key-lever, a plurality of counter-stops adapted to be operated by said lever, a slide resting on said lever and adapted to be interposed between said lever and either of its counter-stops to enable the lever to operate its counter-stops, and a comb common to said key-lever and said slide, to preserve the alinement between said key-lever and its slide. 45
10. The combination with a traveling carriage and tabulating keys for positioning it, of plungers for effecting such positioning and adapted to be selectively operated by said keys, an interponent for each key adapted to be selectively positioned to determine which plunger any key shall operate, and keys adjacent said tabulating keys, depressible to selectively position said interponents. 50
11. The combination with a traveling car- 55

riage and tabulating stops thereon, of a set of tabulating keys for arresting said carriage by said stops, a plurality of plungers for each key, a lever for each key, an interponent for each lever to enable the lever to selectively operate its plungers, and a pivoted frame comprising a shaft on which said interponents are journaled, adapted to move said interponents from one set of 5 plungers to another.

12. The combination with a traveling carriage and tabulating stops thereon, of a set of tabulating keys for arresting said carriage by said stops, a plurality of plungers for each key, a lever for each key, an inter-

ponent for each lever to enable the lever to selectively operate its plungers, a pivoted frame comprising a shaft on which said interponents are journaled, adapted to move said interponents from one set of plungers 20 to another, a toothed comb for guiding said key-levers, comprising extended teeth adapted to guide said plungers and said interponents, and finger-pieces for selectively positioning said interponents by shifting said 25 pivoted frame.
